UNITED STATES PATENT OFFICE.

HARLAN MOORE, OF NEW YORK, N. Y.

RUBBER.

1,100,319.

Specification of Letters Patent. Patented June 16, 1914.

Application filed March 14, 1914. Serial No. 824,747.

To all whom it may concern:

Be it known that I, HARLAN MOORE, of New York, in the county of New York, and in the State of New York, have invented a 5 certain new and useful Improvement in Rubbers, and do hereby declare that the following is a full, clear, and exact description thereof.

The ordinary rubber shoe which has a heel 10 portion, that is of the Oxford style, is troublesome to put on by reason of the close, or snug fit of the heel portion to the shoe, because of the contact of the shoe heel with the top edge of the heel portion of the rubber 15 which bends, or crumples such top edge inward and usually necessitates the thrusting of the fingers into the rubber shoe for the purpose of stretching or pulling the heel portion thereof over the foot. This operation 20 is not only objectionable because of the likelihood of soiling the hand, or glove, but the pressure on the fingers, due to pinching, or squeezing, is disagreeable and sometimes painful.

25 The object of my invention is to overcome these troubles by a simple and inexpensive device which will add little or nothing to the original cost of the rubber and which will at the same time be an advantage in other respects, such, for example, as strengthening the rubber at the heel where it is likely to split from undue pressure, protecting the lower portion of the garment 30 of the wearer from wet, and adding to the comfort of the wearer in cold weather by furnishing additional covering for the foot.

35 My invention may be embodied in various forms and, indeed, besides being applicable to rubbers is also applicable to similar 40 shapes of foot wear, such as slippers, or foot wear of the Oxford style, but in the accompanying drawings I illustrate my invention as adapted to the ordinary Oxford style rubber and in which drawings—

45 Figure 1 is a side elevation showing an Oxford style rubber provided with my invention, illustrating the manner of use of my invention; Fig. 2 is a view, in perspective, of a portion of the rubber showing my 50 device when in its position for use when putting the rubber on.

The rubber 10, shown, is, as has been explained, of the ordinary Oxford type having the heel-protecting portion 11, as usual. To 55 the upper edge of the heel-protecting portion 11, and preferably extending well

around on each side of the rubber forward, in the form of my invention shown in Figs. 1 and 2, is a flap, or lip 12, preferably of some flexible and elastic material, such as 60 rubber of which the rubber shoe itself is made, which along the line 13 that corresponds with the upper edge of the ordinary rubber, is adapted to be turned upward or downward so that in one case it occupies the 65 raised position shown in dotted lines in Fig. 1, and in full lines in Fig. 2, and in the other case the lowered position shown in full lines in Fig. 1, where it is folded, or doubled over and snugly fits, or conforms to the contiguous 70 heel-protecting portion of the rubber, in which last named position it forms a brace, or reinforcement for the rubber around the back of the heel portion and supports it against strains tending to split, or tear it 75 down the back. When in the raised position shown in dotted lines in Fig. 1, and the full lines in Fig. 2, it performs the function of a shoe horn, as clearly shown in dotted lines in Fig. 1, to easily and comfortably guide 80 the foot into the rubber, the top rear edge of the flap affording a convenient handle for the fingers, which are thus entirely out of contact with the shoe. When the rubber is on and the flap, or lip is in such vertical 85 position, it constitutes additional covering for the foot about the ankle over an area not reached by the ordinary Oxford rubber, and hence, is desirable in cold weather for that purpose, and an additional protection against 90 snow, or rain finding its way over the top of the rubber between it and the shoe, is afforded. By reason of the flexibility and elasticity of the flap, it may readily be made 95 to occupy the two positions shown, and as 95 the turn "inside out," so to speak, which takes place in shifting it from its raised to its lowered position places it under some slight tension when in its lowered position, it remains in its lowered position and forms 100 a substantial support, or brace for the heel portion of the rubber. Contiguous to the line 13, which corresponds with the upper edge of the ordinary rubber, the flap is preferably 105 enough less rigid as to cause it to readily bend or turn about such line, or edge.

The flap can be cut out as a part, or integral with the stock forming the rubber upper, or it can be made as a separate piece and afterward attached to the rubber.

If desired, eyelet holes may be provided in the flap for the passage of a lace which may

be tied across the instep to aid in holding the flap in its raised position, or straps may be provided for the same purpose.

Having thus described my invention what 5 I claim is—

1. An article of foot wear of the Oxford type, having a flap at the heel portion which is shiftable vertically from a position below the top edge of the heel portion to one 10 above the same, said flap being flexibly connected with the top edge of the heel portion, its movement taking place about the top edge of the heel portion and the flap reversing when it is shifted from one of its 15 positions to the other.

2. An article of foot wear of the Oxford type, having a flap at the heel portion which

is shiftable vertically from a position below the top edge of the heel portion to one above the same, said flap being of elastic material 20 and reversing when it is shifted from one of said positions to the other.

3. A rubber shoe having a flap at the heel portion which is shiftable vertically from a position below the top edge of the heel portion to one above the same, the flap being of elastic material and its movement taking place about the top edge of the heel portion. 25

In testimony that I claim the foregoing I have hereunto set my hand.

HARLAN MOORE.
